UNITED STATES PATENT OFFICE.

FRANK J. HEINZLER, OF SLATER, MISSOURI.

COMBINATION END-GATE AND SCOOP-BOARD.

1,177,863.

Specification of Letters Patent.

Patented Apr. 4, 1916.

Application filed October 7, 1915. Serial No. 54,615.

To all whom it may concern:

Be it known that I, FRANK J. HEINZLER, a citizen of the United States, residing at Slater, in the county of Saline and State of Missouri, have invented certain new and useful Improvements in Combination End-Gates and Scoop-Boards; and I do declare the following to be a full, clear, and exact description of the invention, such as will enable others skilled in the art to which it appertains to make and use the same.

This invention relates to improvements in wagons and more particularly to end gates therefor, and has for its object to provide a simply constructed means for holding the end gate in either open or closed position on the wagon body.

A further object is to provide an end gate in the form of a scoop board.

20 A still further object is to provide brackets for holding the scoop on the wagon body, said brackets being adjustable to any sized wagons.

An additional object is to provide a pair 25 of brackets which may be applied to any wagon without the use of driven fastenings of any type.

With the above and minor objects in view, my invention resides in the novel features 30 of construction, combination and arrangement of parts which will hereinafter be more particularly described and claimed, and shown in the drawings wherein:

Figure 1 represents a side elevation of a 35 portion of a wagon body having my invention applied thereto, showing the scoop board in both open and closed position; Fig. 2 is an end view of the wagon body with the scoop board in upright or inactive position; Fig. 3 is a transverse section taken on the line 3—3 of Fig. 1; Fig. 4 is a detail 40 transverse section taken on the line 4—4 of Fig. 1, and Figs. 5, 6, 7, 8, and 9, are detail perspective views of the various parts of one 45 of the brackets which I employ.

In the accompanying drawings, I have shown my invention applied to a wagon body 1 having the usual side boards 2 and the supplemental sides 3, the end of the 50 wagon 1 being closed by a scoop board 4.

The scoop board 4 comprises a bottom 5 upon which are mounted a pair of laterally extending pivot studs 6, and side flanges 7.

The end gate in the form of the scoop 4 55 is mounted in position on the wagon body by my improved brackets, here shown as substantially L-shaped, each with a hori-

zontal arm 8 having a head 9 on one end thereof, said head having a jaw 10 depending therefrom and adapted to abut one side 60 of the rearmost cross beam 11 of the wagon body. This jaw 10 forms one portion of an attaching clamp, the complementary portion thereof comprising a slide 12 movable on the arm 8 and having a depending jaw 13 65 adapted to abut the opposite side of the cross beam 11. The slide 12 is slotted as shown at 14 to receive a stud 15 whose outer end is threaded to receive a clamping nut 16. This construction allows the slide to be moved 70 toward the stud 15 until the jaw 13 contacts with the beam 11, thereby clamping said beam between the jaws 10 and 13, the nut being screwed down tightly when the slide has been moved to its correct position. It is 75 obvious that two of these L-shaped brackets are provided, one on each side of the wagon body adjacent its end, but as both are constructed in the same manner, only one will be described.

The arm 8 is preferably provided with an inwardly extending flange 17 which projects laterally therefrom and is adapted to underlie the bottom of the wagon body 1. The slide 12 is provided with a similar flange 18 85 from which the jaw 13 depends as clearly illustrated in Figs. 1 and 4. The flange 17 acts as one portion of a vertical attaching clamp, the other portion thereof consisting of a hook 19 which receives the upper edge 90 of the side board 2, a notch 20 being formed on the supplemental side when the same is placed on the wagon. The hook 19 is shown formed on one end of an adjustable arm 21 whose lower end is slotted as shown at 22 to 95 receive the studs 23 whose free ends are threaded to receive the clamping nuts 24 for securing the arm in adjusted position. It is obvious that by moving the hook 19 toward the flange 17, the side board 2 of the 100 wagon will be tightly clamped therebetween and aid the horizontal clamp in securing the bracket to the wagon body 1.

Each of the heads 9 has provided in its upper edge a pair of bearing openings 25 105 and 25' which are adapted to receive the pivot studs 6 on the scoop board. The bearing openings on one head are adapted to align with those on the other head, the outermost pair of aligned openings 25 receiving 110 the pivot studs 6 when the scoop board is in upright or inactive position, while, when the scoop board is down as shown in dotted lines in Fig. 1, the pivot studs 6 will occupy the

inner bearing 25'. By reference to the drawings, particularly Fig. 5, it will be seen that the bearings 25 and 25' in each head are in the same horizontal plane, and that they 5 communicate with each other, being partially separated by the raised portion 25a. This construction permits the pivot studs 6 to move from one set of bearings to the other by riding over the portion 25a, thus 10 said studs remain in engagement with the heads 9 at all times. This arrangement allows for the thickness of the bottom 5 of the scoop board and permits the same to tightly close the end of the wagon body 15 when in upright position, and when in lowered position, the lower edge of the bottom 5 will closely contact with the outer end edge of the bottom and prevent any loss of grain or other materials loaded into the 20 wagon.

An additional upright arm 26 is formed on the bracket and is adapted to have pivotally connected to its upper free end an arm 27 which aids in holding the scoop board in either raised or lowered position. The free end of the arm 27 extends through the bearing 28 carried by the bottom of the scoop board 4, said free end receiving one end of a rod 29 whose free end has formed thereon 25 a hook 30. The bottom 5 of the scoop board also carries the clips 31, the rods 29 being adapted to spring under these clips 31 when the scoop board is used to close the wagon body as shown in full lines in Fig. 1. When, 30 however, it is desired to lower the scoop board, the arms 29 are sprung from under the clips, which will allow the board to be moved into the dotted line position as shown in this figure, the hooks 30 coacting 35 with the bearings 28 to hold the board in operative position. The arms 27 are prevented from getting out of alinement with the rods 29 by the guides 32.

From the foregoing description, it will 45 be seen that I have provided brackets for mounting an end gate or scoop board to a wagon which may be readily adjusted to any size wagon, and quickly taken off or put on any wagon without the aid of any driven 50 fastenings.

While I have described the elements best adapted to perform the functions, it is obvious that various changes in the form and proportion of these brackets or the means 55 for holding the gate in raised or lowered position, may be resorted to without departing from the spirit or sacrificing any of the principles of this invention.

I claim as my invention:

60 1. In combination, a wagon body and an

end gate therefor; of a pair of detachable L-shaped end brackets, each comprising an upright attaching clamp adapted to receive the side of a wagon, a horizontal arm, a depending jaw on said arm, a slide movable on 65 said arm and having a depending jaw, said jaws being adapted to clamp the cross beam of a wagon therebetween.

2. In combination, a wagon body and an end gate therefor; of a pair of detachable L-shaped end gate brackets, each comprising an upright attaching clamp adapted to receive the side of a wagon, a horizontal arm, a depending jaw on said arm, a flange extending from said arm beneath the wagon 75 body, a slide movable on said arm and having a flange extending beneath the first mentioned flange, a jaw on said slide, said jaws being adapted to clamp the cross beam of a wagon therebetween.

3. In combination, a wagon body and an end gate therefor; of a pair of detachable L-shaped end gate brackets each comprising a horizontal attaching clamp, an upright arm having a hook on one end, and a laterally extending flange underlying the wagon 85 body.

4. In combination, a wagon body and an end gate therefor; of a pair of detachable L-shaped end gate brackets, each comprising a horizontal arm, a depending jaw thereon, a slide movable on said arm and having a depending jaw, said jaws being adapted to clamp the cross beam of a wagon therebetween, an upright arm having a hook on 95 one end, and a laterally extending flange underlying the wagon body.

5. The combination with a wagon body, of an end gate therefor, laterally extending pivot studs projecting from each side of said 100 gate, a bracket disposed on each side of said body, and a head on each bracket, each of said heads having a pair of bearing openings therein, disposed in the same horizontal plane and communicating with each other, the bearing openings in one head being 105 alined with those in the other, said pivot studs being disposed in one of said alined openings when the gate is down, and moving into the other as the same is raised, whereby 110 a tight connection is maintained between the wagon body and gate.

In testimony whereof I have hereunto set my hand in presence of two subscribing witnesses.

FRANK J. HEINZLER.
